GASOLINE VAPORIZER

Eddie Anderson, Del Paso Heights, Calif.

Application August 30, 1955, Serial No. 531,501

3 Claims. (Cl. 48—102)

This invention relates in general to new and useful improvements in carburetion systems for internal combustion engines, and more specifically to an improved gasoline vaporizer.

It is well known that the present-day carburetor is inefficient inasmuch as the gasoline supplied thereby is broken up into a fine spray to result in the complete burning thereof in the cylinders of the engine. In recent years, it has been found that a gasoline vapor will produce the maximum efficiency. However, it is difficult to produce such a vapor and the normal manner of producing the vapor will not produce instantaneous starting as is desired by most users of internal combustion engines.

It is therefore a primary object of this invention to provide a gasoline vaporizer to be used in conjunction with a conventional carburetion system, the gasoline vaporizer being of such a nature whereby it may be cut in after the internal combustion engine has been started and run for a while.

Another object of this invention is to provide an improved gasoline vaporizer which is so constructed whereby the gasoline is vaporized due to the spraying of the gasoline onto a heated vaporizing plate, the vaporizing plate being heated from the heat of the exhaust manifold of the internal combustion engine to which the gasoline vaporizer is attached.

Still another object of this invention is to provide an improved control system for gasoline vaporizers, the control system including a series of valves which are electrically controlled in response to the energization of a thermostatic switch by proper heating of an internal combustion engine exhaust manifold, the electrically controlled valve including a normally open valve in the main fuel line of the internal combustion engine and the other normally closed valves in a gasoline supply line for the gasoline vaporizer and in a vapor supply line from the gasoline vaporizer.

A further object of this invention is to provide an improved gasoline vaporizer which includes an accumulator tank having a heated vaporizer plate in the bottom part thereof, there being provided a suitable gasoline delivery tube overlying the vaporizer plate and having spray nozzles for projecting sprays of gasoline against the vaporizer plate, and there also being provided a pressure actuated valve responsive to the pressures within the accumulator tank to control the delivery of gasoline thereto.

These, together with other objects and advantages which will become subsequently apparent, reside in the details of construction and operation as more fully hereinafter described and claimed, reference being had to the accompanying drawings forming a part hereof, wherein like numerals refer to like parts throughout, and in which:

Figure 1 is a side elevational view of an internal combustion engine and shows mounted thereon a preferred form of gasoline vaporizer;

Figure 2 is an enlarged elevational view of the main part of the gasoline vaporizer and shows the same removed from the internal combustion engine, a portion of the accumulator tank of the gasoline vaporizer being broken away and shown in section in order to clearly illustrate the details of the interior thereof;

Figure 3 is an enlarged top plan view of the accumulator tank of Figure 2 and shows further the details thereof;

10 Figure 4 is an enlarged fragmentary transverse vertical sectional view taken through the accumulator tank and shows the relationship of the gasoline delivery tube with respect to the vaporizer plate;

15 Figure 5 is a perspective view of a modified form of accumulator tank and shows the same mounted on an exhaust manifold for a V-type engine; and

20 Figure 6 is an enlarged horizontal sectional view taken through an adapter block for attachment to a carburetor whereby the carburetor may be converted to use of gasoline vapors.

25 Referring now to the drawings in detail, it will be seen that there is illustrated a conventional type of internal combustion engine which is referred to in general by the reference numeral 10. The internal combustion engine 10, among other features, includes an intake manifold 12, an exhaust manifold 14, and a carburetor 16 mounted on the intake manifold 12. Extending from the fuel pump (not shown) and connected to the carburetor 16 for supplying gasoline thereto is a main fuel supply line 18. Also mounted on the internal combustion engine 10 and utilizing the operation thereof is a gas-fuel vaporizer which is the subject of this invention, the gasoline vaporizer being referred to in general by the reference numeral 20.

30 The gasoline vaporizer 20 includes an accumulator tank which is referred to in general by the reference numeral 22 and is best illustrated in Figures 2, 3 and 4. The accumulator tank 22 includes a generally horizontal cylindrical tank portion 24 which has the extreme 35 bottom thereof formed by a relatively thick vaporizer plate 26. Extending upwardly from the central part of the tank portion 24 is an accumulator dome 28.

35 Extending into the tank portion 24 to one end thereof is a gasoline delivery tube 30. The gasoline delivery tube 30 overlies the vaporizer plate 26 and is provided with a plurality of longitudinally spaced, downwardly projecting spray nozzles 32. The spray nozzles 32 direct gasoline to the vaporizer plate 26 for the purpose of vaporizing the same.

40 45 In order that the accumulator tank 22 may be mounted on the exhaust manifold 14, the vaporizer plate 26 is provided at opposite ends thereof with outwardly projecting ears 34. Extending upwardly through the ears 34 and around the exhaust manifold 14 are U-bolts 36 which secure the accumulator tank 22 to the exhaust manifold 14 in such a manner that the vaporizer plate 26 rests directly upon the exhaust manifold 14 and receives heat therefrom.

50 55 Inasmuch as the vaporizer plate 26 is heated, when gasoline is sprayed onto the upper surface of the vaporizer plate 26 through the spray nozzles 32, the gasoline will be immediately vaporized and will fill the accumulator tank 22.

55 60 In order that the volume of flow into the accumulator tank 22 through the gasoline delivery tube 30 may be varied, there is mounted in the gasoline delivery tube 30 a volume control valve 38. The volume control valve 38 is of the conventional needle valve type and is utilized to control the flow of gasoline into the gasoline delivery tube 30.

65 70 Connected to the gasoline delivery tube 30 through its connection to the valve 38 is a gasoline supply line 40.

Disposed adjacent the valve 38 within the gasoline supply line 40 is a pressure actuated valve 42. The pressure actuated valve 42 includes a diaphragm assembly 44 for controlling the operation of the valve 42. Connected to the diaphragm assembly 44 is a control line 46 whose opposite end is connected to the accumulator dome 28. Thus, the valve 42 is controlled by the pressure of gasoline vapor within the accumulator tank 22. When the pressure of the gasoline vapor within the tank 22 rises, due to the connection of the control line 46 to the accumulator dome 28, the diaphragm 44 is actuated to close the valve 42, thereby limiting the supply of gasoline to the interior of the accumulator tank 22. The upper end of the dome 28 is also provided with a safety release valve 48 in the event the valve 42 does not function properly.

Referring now to Figure 1 in particular, it will be seen that the gasoline supply line 40 has mounted therein adjacent the valve 42 a gasoline reservoir 50. This is to assure maximum supply of gasoline to the valve 42 at all times. The gasoline supply line 40 extends from the reservoir 50 to the main fuel line 18 and is connected thereto by means of a T-fitting 52. Thus, gasoline is supplied to the gasoline supply line from the main fuel line 18.

In the operation of the gasoline vaporizer 20, it is not desired that fuel be supplied to the accumulator tank 22 until such time as the vaporizer plate 26 reaches the desired temperature for vaporizing gasoline. This is accomplished by placing in the main fuel line 18 between the fitting 52 in the carburetor 16 a normally opened electrical controlled valve 54. A similar, normally closed electrically controlled valve 56 is mounted in the gasoline supply line 40. A third electrically controlled valve 58 is mounted in a vapor supply line 60 which extends between the accumulator dome 28 and an adapter block 62 carried by the carburetor 16. The valve 58 is also normally closed.

In order that the valves 54, 56 and 58 may be controlled there is provided a thermostatically controlled switch 64 which is mounted on the exhaust manifold 14. Extending from the thermostatic control switch 64 to the battery (not shown) carried by the vehicle of which the internal combustion engine 10 is a part is a wire 66. The wire 66 is preferably connected to the ignition switch (not shown) of the vehicle. The wire 66 is also connected to the valves 54, 56, and 58 in series and finally grounded.

In the operation of the gasoline vaporizer 20, the engine 10 is started in the normal manner utilizing the carburetor 16. Then after the exhaust manifold 14 has reached a predetermined temperature, the thermostatic switch 64 is actuated. At this time the valve 54 is closed and the valves 56 and 58 opened. The opening of the valve 56 permits gasoline to flow into the accumulator tank 22 and the resultant vaporization of the gasoline. The gasoline vapor then passes into the carburetor 16 through the block 62 by means of the vapor supply line 60, the valve 58 now being open. The gasoline vapor within the accumulator tank 22 is retained at a constant pressure by means of the valve 42.

Referring now in particular to Figure 6, it will be seen that there is illustrated details of the fuel block 62. The fuel block 62 includes a generally L-shaped housing 68 which includes an inlet fitting 70 in one end thereof for receiving the vapor supply line 60. Communicating with the fitting 70 is a first passage 72 which terminates in an end wall 74. The end wall 74 has an opening 76 therethrough which is controlled by means of a needle valve 78. Disposed normal to the passage 72 is a passage 80 into which the gasoline vapor flows after passing the needle valve 78.

The extreme end of the passage 80 remote from the needle valve 78 is provided with a fitting 82 which may

be utilized in the connection of the fuel block 62 to the carburetor 16 in any desired manner. Flow of air into the passage 80 through a vent opening 84 is controlled by means of a needle valve 86 in order that the proper air mixture may be obtained.

In order that the internal combustion engine 10 will operate at an idling speed, there is provided a small gasoline vapor supply line 88 which is tapped into the passage 72. This line 88 is connected into the venturi (not shown) mounted in the carburetor 16, as is best illustrated in Figure 1.

While the fuel block 62 has been illustrated and described with respect to this invention, it is to be understood that it is not necessary, and may be replaced by other types of control valves. For example, in cases of butane gas installation, special types of diaphragm control needle valves are utilized. Such a needle valve may be used in conjunction with the gasoline vaporizer 20 in lieu of the fuel block 62.

Referring now to Figure 5 in particular, it will be seen that there is illustrated a modified form of accumulator tank which is referred to in general by the reference numeral 90. The accumulator tank 90 includes a horizontal tank portion 92 in an upstanding accumulator dome 94. Positioned in the lower part of the tank portion 92 is a vaporizer plate 96 similar to the vaporizer plate 26. The vaporizer plate 96 is spaced above the bottom of the tank portion 92 and forms in conjunction therewith an exhaust passage 98. The passage 98 has communicated therewith exhaust lines 100 which are in turn connected to the interior of an exhaust manifold 102. The exhaust manifold 102 is preferably for a V-type engine and is of a nature whereby the accumulator tank 22 could not be conveniently set thereon.

When the accumulator tank 90 is utilized, no other changes are required in the gasoline vaporizer 20. The system remains the same as that described with respect to Figure 1, although, if desired, there may be an accumulator tank 90 on each of the two exhaust manifolds 102 of a V-type engine.

From the foregoing description of the invention, it will be readily apparent that there has been devised a gasoline vaporizer which may be conveniently mounted on existing designs of an internal combustion engine and which may be utilized in conjunction with the normal fuel system thereof for operating the internal combustion engine with maximum efficiency once the internal combustion engine has been started and the exhaust manifold thereof has been warmed up to the necessary temperature for vaporizing the gasoline.

By preheating and vaporizing the fuel before it enters into the carburetor, a more complete mixing of the fuel and air is possible. This results in a fuel-air mixture which is more completely burned to increase the efficiency of the internal combustion engine. Further, by eliminating raw fuel from the cylinders of the internal combustion engine, the quantity of sludge formed is greatly reduced.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A gasoline vaporizer comprising an accumulator tank, a vaporizer plate disposed at the bottom of said accumulator tank, a gasoline delivery tube in said accumulator tank above said vaporizer plate, said gasoline delivery tube having downwardly directed spray nozzles for directing gasoline on said vaporizer plate, means for heating said vaporizer plate from an exhaust manifold,

a gasoline supply line connected to said gasoline delivery tube exteriorly of said accumulator tank, a fitting for connecting said gasoline supply line to a main fuel line for a carburetor, a normally open electrically controlled valve for positioning in the main fuel line intermediate said fitting and the carburetor, a normally closed electrically controlled valve in said gasoline supply line, a thermostatic switch adapted to be connected to an exhaust manifold and controlled by heat therefrom, and wiring connecting said electrically controlled valves and said switch to an electrical source.

2. A gasoline vaporizer comprising an accumulator tank, a vaporizer plate disposed at the bottom of said accumulator tank, a gasoline delivery tube in said accumulator tank above said vaporizer plate, said gasoline delivery tube having downwardly directed spray nozzles for directing gasoline on said vaporizer plate, means for heating said vaporizer plate from an exhaust manifold, a gasoline supply line connected to said gasoline delivery tube exteriorly of said accumulator tank, a fitting for connecting said gasoline supply line to a main fuel line for a carburetor, a normally open electrically controlled valve for positioning in the main fuel line intermediate said fitting and the carburetor, a normally closed electrically controlled valve in said gasoline supply line, a thermostatic switch adapted to be connected to an exhaust manifold and controlled by heat therefrom, and wiring connecting said electrically controlled valves and said switch to an electrical source.

3. A gasoline vaporizer comprising an accumulator

tank, a vaporizer plate disposed at the bottom of said accumulator tank, a gasoline delivery tube in said accumulator tank above said vaporizer plate, said gasoline delivery tube having downwardly directed spray nozzles for directing gasoline on said vaporizer plate, means for heating said vaporizer plate from an exhaust manifold, a gasoline supply line connected to said gasoline delivery tube exteriorly of said accumulator tank, a fitting for connecting said gasoline supply line to a main fuel line for a carburetor, a normally open electrically controlled valve for positioning in the main fuel line intermediate said fitting and the carburetor, a normally closed electrically controlled valve in said gasoline supply line, a thermostatic switch adapted to be connected to an exhaust manifold and controlled by heat therefrom, and wiring connecting said electrically controlled valves and said switch to an electrical source, a pressure actuated valve in said gasoline supply line intermediate said normally closed electrically controlled valve and said accumulator tank, and a control line from said accumulator tank to said pressure actuated valve.
